Primary Examiner — Rosemary K Tarcza*Assistant Examiner* — Leah E Hoeferkamp(74) *Attorney, Agent, or Firm* — K&L Gates LLP(57) **CLAIM**

The ornamental design for an auxiliary contacts for circuit breaker as shown and described herein.

DESCRIPTION

FIG. 1 is a front perspective view of an auxiliary contacts for circuit breaker showing the new design;

FIG. 2 is a rear perspective thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof, wherein.

Lines shown as broken lines form no part of the claimed design.

1 Claim, 8 Drawing Sheets(56)
